UNITED STATES PATENT OFFICE.

EUGÈNE LECOCQ, OF BRUSSELS, BELGIUM.

COKE OVEN.

Application filed February 11, 1918. Serial No. 216,565.

(GRANTED UNDER THE PROVISIONS OF THE ACT OF MARCH 3, 1921, 41 STAT. L., 1313.)

To all whom it may concern:

Be it known that I, EUGÈNE LECOCQ, a subject of the King of Belgium, residing at Brussels, in the Kingdom of Belgium, have invented certain new and useful Improvements in Coke Ovens (and for which I filed application for patent in Belgium on July 8th, 1916), of which the following is a specification.

10 This invention relates to coke ovens of the kind in which horizontal coking chambers are combined with side-walls provided with vertical flues forming lateral heating chambers, said ovens having no regenerators and working with or without recuperation of the by-products.

A first object of my invention is to secure a regular and uniform coking in the whole length of the coking chambers and consequently a more regular and uniform temperature than hitherto obtained in the said coking chambers.

Another object of my invention, in direct connection with the purpose just mentioned, is to avoid that the flues, which are arranged in the heating chambers and which do not contribute to the heating but are used for the escape of the burnt gases, should disturb the regular operation of the coking chamber.

30 And a further object of my invention is to reduce the loss of heat by radiation in the lower part or foundation of the structure and on the other hand to compensate by an excess of heat the loss of heat by radiation in some other parts of the oven, for instance in that part which is adjacent to the heating flues at both ends of the heating chambers.

With these objects in view my invention essentially consists in some special arrangements and combinations of circulation channels and also of the conduits for the distribution of air and gas as will be herein-after fully described and pointed out in the appended claims.

In the accompanying drawings:

Fig. 1 is a front view of the ovens comprised in a single structure, or in a battery of ovens, said view corresponding to a section taken on line 1—2, Fig. 3.

Fig. 2 is a vertical section through the coking chamber of an oven, taken on line 3—4, Figs. 1 and 7.

Fig. 3 is a vertical section through the

flues of a heating chamber, taken on line 55 5—6, Figs. 1 and 7.

Fig. 4 is a vertical transverse section through the first flue of the heating chamber and the smoke collecting channel, taken on line 7—8, Fig. 3.

Fig. 5 is a vertical section through the descending flue for the escape of the burnt gases, taken on line 9—10, Fig. 3.

Fig. 6 is a horizontal section through the collecting galleries and the air channels in 65 the foundation of the structure, taken on line 11—12, Fig. 3.

Fig. 7 is a horizontal section through the gas-distributing chambers and the air channels under the hearth, taken on line 13—14, 70 Figs. 2 and 3.

Fig. 8 is a horizontal section through the lower part of the heating chambers and coking chambers, taken on line 15—16, 75 Fig. 3.

Figs. 9 and 10 are two diagrammatic views showing, in vertical section, the distribution of the air into the vertical flues of the heating chambers. The said views do not correspond exactly to a section taken 80 on line 3—4, Figs. 1 and 7, the air channels under the hearth, having been displaced to better illustrate the manner in which they cooperate with the flues of the heating chambers.

The coking oven which has been illustrated comprises, as ordinarily, a foundation or lower structure T provided with two galleries A for inspection, a central gallery B for the air, two lateral pairs of galleries D D₁ for the air and two collecting galleries C which are placed between the central gallery B and the lateral galleries D D₁ (Figs. 3 and 6).

The galleries A (Figs. 2, 3 and 6) provided for inspection, are open to the atmosphere at one end A₁ (Fig. 6) and are joined together at the other end by a gallery A₂ (Fig. 8) communicating with the central gallery B. This latter is closed at the opposite end B₁ (Fig. 6) and communicates through little ducts b (Figs. 2, 3 and 6), passing under the collecting galleries C, with the lower lateral galleries D which are in communication with the upper lateral 105 galleries D₁ whence the air is conducted through passages d into air channels E₁ E₂ E₃ E₄ (Figs. 2 and 7) which are arranged

under the hearth of each coking chamber U as will be further described.

Above the foundation or lower structure T, just described, is placed the upper structure or battery of ovens comprising the horizontal coking chambers U (Figs. 2, 4, 5 and 8) each placed between two heating chambers V (Figs. 1, 3, 4 and 8). These heating chambers are provided with vertical flues V₁ which are numbered 1, 2, 3, 4, 28 in Fig. 3, and form four groups: a first group comprising the flues 1, 2, 3, 4, 5, 6, 7; a second group comprising the flues 9, 10, 11, 12, 13, 14; a third group comprising the flues 15, 16, 17, 18, 19, 20, and a fourth group comprising the flues 22, 23, 24, 25, 26, 27, 28. Between the first and second groups, a flue 8 is provided for the escape of the burnt gases from the said groups of flues; 10 a similar flue 21 is provided between the third group and the fourth group for the escape of the burnt gas from the said groups of flues. The said flues 8 and 21, which will be called hereafter "descending flues" communicate through passages f (provided with dampers g, Fig. 5) with the collecting galleries C already described.

The vertical flues 1-28 are intercommunicating at their upper part as shown in Fig. 3, and are situated, as usually, under the channels N giving access to the heating chambers.

P (Fig. 3) is a channel for the capture of smoke and M are four dampers (shown only in dotted lines) which are used when it is desired to work without recuperation of the by-products.

The flues 1 to 7; 9 to 14; 15 to 20 and 22 to 28 must be supplied with gas and air so as to secure the regular and uniform heating of the whole length of each coking chamber U. This feeding takes place as follows:

The gas is supplied through gas pipes G, which are arranged in the galleries A for inspection, at the front and rear ends of the ovens (Figs. 2 and 3). On each pipe G are branched, for each heating chamber, three cocks r. One of these cocks (on each side of the oven) feeds through a pipe r₁ the first flue 1 (resp. the last flue 28). The second cock (on each side of the oven) feeds through a pipe r₂ a gas chamber a communicating through passages a₁ with the flues 2 to 7, at one end of the oven and with the flues 22 to 27 at the other end of the oven. The third cock feeds (on each side of the oven) through a pipe r₃ a gas chamber a₂ communicating through passages a₃ with the flues 9 to 14, resp. 15 to 20.

In other words, the feeding system for the gas comprises, for each half of a heating chamber, three cocks r branched upon the same gas pipe G, a pipe r₁ leading directly to the first flue 1 (or to the last flue 28), a

pipe r₂ leading to a gas chamber a, and a pipe r₃ leading to a gas chamber a₂.

The air is conducted through the galleries A A₂ to the central gallery B, passes through the ducts b into the lateral galleries D; then into the upper lateral galleries D₁ and finally through the passages d, provided with dampers s into the air channels under the hearth of each coking chamber. These air channels E₁ E₂ E₃ E₄ (Figs. 2 and 7) are arranged in such a manner that each of them feeds a group of flues 1 to 7; 9 to 14; 15 to 20 or 22 to 28.

Further the arrangement of said channels E₁ E₂ E₃ E₄ is such that the first air channel E₁ (Fig. 2) is supplied with air from the galleries D₁ on the left hand side of the oven, whilst the second air channel E₂, which is coaxial with the first channel E₁, is supplied with air from the lateral galleries D₁ on the right hand side of the oven.

Similarly, the third air channel E₃ is supplied with air from the lateral galleries D₁ on the left hand side of the oven and the fourth air channel E₄ from the lateral galleries D₁ on the right hand side of the oven.

The operation of the oven is as follows:

The gas which is supplied through the cocks r to the end flues 1 and 28 and also to the gas chambers a and a₂ combines in the vertical flues of the heating chambers with the air coming through the air channels E₁ E₂ E₃ E₄ under the hearth (through A A₂ B b D and D₁ as already described) and which is supplied to the flues through passages e (Figs. 2-4 and 7).

During the operation, the draft in each half heating chamber can be controlled by means of dampers g, placed in the passages f. The burnt gases, circulating as shown by dotted arrows in Fig. 3, pass into the descending flues 8 and 21 and are conducted through the passages f into the collecting galleries C which join in a channel H conducting the burnt gases to boilers or similar apparatuses.

For the sake of clearness, in the several figures of the drawings, the way followed by the gas is shown by full black arrows; the way followed by the air by thin arrows and the way followed by the burnt gases by means of arrows traced in dotted lines.

It will be observed that in the oven constructed as described, any loss of heat resulting from the radiation of heat in the foundation or lower structure is practically avoided, as indeed the collecting galleries C are surrounded on all sides by the air circulating galleries A B b D D₁.

On the other hand the loss of heat which always takes place by radiation at the ends of the oven, can be easily compensated by the production of an excess of heat in the end flues 1 and 28, said flues being supplied with gas through the gas pipes r₁ which are

independent of the pipes r_2 r_3 supplying gas to the gas chambers a a_2 , each feeding a group of six vertical flues.

The air is uniformly distributed in each 5 vertical flue of any group of flues, which is supplied with air by a given air channel E_1 E_2 E_3 or E_4 as indeed, as it will clearly appear from an inspection of the diagrammatic views, (Figs. 9 and 10) whatever may 10 be the vertical flue, the way followed by the gas, (from the inlet of the air to the outlet of the burnt gases through the descending flue of the group) is the same for the several flues of any group.

15 On the other hand, the arrangement of the descending flues or outlet flues 8 and 21 (Fig. 3) for the burnt gases, between two vertical heating flues 7 and 9—or 20 and 22, has the result that heat will be transmitted 20 by conductivity from the heating flues 7-9 and 20-22 to said descending flues in such a manner that insufficient heating of the coal in the coking chamber will be avoided in the part of the coking chamber in front of 25 the descending flues.

If it is desired to run the oven without recovering the by-products, the four dampers M (shown in dotted lines Fig. 3) are closed.

30 Air is then introduced through the vertical openings N provided in the axis of the heating chambers in the upper part of the oven structures whilst the gas, resulting from the distillation, is sent in the upper 35 horizontal channel of the heating chamber, through passages, not shown on the drawing but provided between the charging openings Z and the channels N and P . Four circuits are then produced in each heating chamber: 40 The burnt gases descend in the four flues 1, 2, 3, 4, enter into the air channel E_1 under the hearth, re-ascend in the three next flues 5, 6, 7 and escape through the descending flue 8; in the second circuit, the gases descend in the flues 12, 13, 14, enter into the air channel E_2 , re-ascend in the flues 9, 10, 45 11, and escape also through the descending flue 8.

50 The third and fourth circuits take place in a similar manner in the second half of the heating chamber.

What I claim is:

1. In a coke-oven of the kind described, horizontal coking chambers, heating chambers arranged on opposite sides of each coking chamber, each of said heating chambers being divided into a plurality of flues, the said flues being arranged in groups of heating flues with a single descending exhaust flue between adjacent groups with which the heating flues are connected, gas chambers connecting with the groups of heating flues to supply gas thereto, separate gas conduits supplying gas to the end heating flues where- 65 by an excess of heat may be produced in the

end heating flues, and air channels arranged under the hearth of the coking chambers and connected to the groups of heating flues to supply air thereto.

2. In a coke-oven of the kind described, 70 coking chambers, heating chambers arranged laterally of the coking chambers and each divided into a plurality of flues, two of the flues of each chamber being exhaust flues and spaced apart and between two adjacent 75 groups of the other flues, a plurality of gas chambers connected to the heating flues to supply gas, independently of each other, to separate groups of heating flues, additional means for supplying gas to the end heating flues in the end of each chamber whereby an excess of heat may be produced in the said end heating flues, a plurality of air channels arranged each under a part of the hearth of each coking chamber, air supplying galleries arranged under the said air channels at both ends of the structure, the said galleries being alternately connected to two air channels co-axially disposed.

3. In a coke-oven of the kind described, 80 in combination, horizontal coking chambers, heating chambers laterally arranged on each side of the coking chambers, and each divided into four groups of vertical heating flues and two descending flues for the escape of 85 the burnt gases, each of said descending flues being arranged between two adjacent groups of vertical heating flues, a plurality of gas chambers arranged under the heating chambers, each of said gas chambers supplying 90 with gas, a group of vertical heating flues, independently of the others, in a same heating chamber; two separate gas-supplying devices for the end flues of each heating chamber one for each end flue of each end chamber, 95 a plurality of air channels under the hearth of each coking chamber, said channels being arranged in pairs in the axis of each other and each pair supplying with air 100 two adjacent groups of vertical heating flues in corresponding heating chambers, air galleries arranged laterally under the air channels, at both ends of the oven, said galleries 105 supplying air on one side of the oven to the air channel corresponding to a first group of vertical heating flues and on the other side 110 of the oven, to the air channel corresponding to a second group of vertical heating flues, adjacent to the first group, and so on, and collecting galleries for the burnt gases, said 115 collecting galleries being situated between the lateral air galleries and a central air gallery, in communication with the lateral air galleries.

4. In a coke-oven of the kind described, 120 in combination, horizontal coking chambers, heating chambers adjacent to said coking chambers and each divided into four groups of vertical heating flues and two descending flues for the escape of the burnt 125 gases.

gases, each of said descending flues being arranged between two adjacent groups of vertical heating flues, means for collecting and removing the burnt gases from the descending flues, means whereby the said groups of vertical heating flues are supplied with gas, independently of each other, air-channels under the hearth of each coking chamber, the said air-channels being arranged in such a manner that two adjacent groups of vertical heating flues in a same heating chamber are supplied with air from opposite ends of the oven, air-galleries ar-

ranged laterally at both ends of the oven, 15 said galleries communicating in alternance with the said air channels and passing under and around the burnt gas, collecting and removing means whereby heat of the lower structure of the oven can be recuperated and the loss of heat can be practically avoided. 20

In testimony whereof I have affixed my signature in presence of two witnesses.

EUGÈNE LECOCQ.
